UNITED STATES PATENT OFFICE.

ROBERT L. SLONAKER, OF WHEELING, WEST VIRGINIA.

HAT-PIN PROTECTOR.

1,034,316.

Specification of Letters Patent. Patented July 30, 1912.

Application filed February 21, 1911. Serial No. 609,966.

To all whom it may concern:

Be it known that I, ROBERT L. SLONAKER, a citizen of the United States, residing at Wheeling, in the county of Ohio and State 5 of West Virginia, have invented new and useful Improvements in Hat-Pin Protectors, of which the following is a specification.

This invention relates to improvements in protectors for ladies' hat pins and the object 10 of the invention is to provide a device of this character which will effectively engage and protect the projecting end of a hat pin and which, while firmly sustaining itself upon the pin, may be readily removed therefrom when desired.

With the above object in view, the invention resides in the novel construction and arrangement of parts hereinafter more fully described and claimed.

20 In the accompanying drawings there has been illustrated a simple and preferred embodiment of the improvement and in which drawings, Figure 1 is an elevation of the improved protector, showing the same applied to a hat pin. Fig. 2 is a similar view, the protector being shown in section.

The projecting points of ladies' hat pins have become a menace to the safety of the public, especially upon crowded thoroughfares, and it is the primary object of the 30 present invention to obviate these dangers and at the same time to provide a protector for the projecting point of the pin, which is of an ornamental design, thereby adding to 35 the attractiveness of the hat.

In the accompanying drawings, the numeral 1 designates an ordinary hat pin. The pin, in the present instance, is provided with an ornamental head 2.

40 The numeral 3 designates the pin point protector. This protector comprises a casing 4 having its lower end substantially cone-shaped and provided with an opening 5 through which the end of the pin is adapted 45 to be inserted. Arranged within the cone-shaped casing 4 is a clutch member 6. This clutch is constructed of a single strip of resilient material and comprises what 50 may be termed a body or head 7 having 55 downwardly inclined oppositely arranged arms 8 and the lower extremities of each of the said arms are formed with lips 9. The 60 lips 9 are arranged opposite each other and are preferably serrated so as to firmly engage the pin 1. The clutch 6 is of a size 65 sufficient to have its arms contact the cone-

shaped surface of the casing 4 and as the said clutch is moved downwardly in a manner presently to be set forth, the arms are compressed so that the lips 9 are brought 60 tightly together and thus securely engaging with the pin 1. Connected with the upper or body portion 7 of the clutch is a tube 10, and the said tube is provided with a hollow, preferably cylindrical head 11. Both the 65 head 11 and the casing 4 are adapted to be of some ornamental design so as to add to the attractiveness of the same. The tube 10 projects through an opening 12 provided by the top 13 of the casing 4, and the upper 70 portion of the said casing is preferably rectangular in formation. Surrounding the portion of the tube connected with the body 7 of the clutch 6 within the casing 4, is a helical spring 14. This spring is adapted 75 to exert pressure between the top 13 of the casing and the body 7 of the clutch so as to force the arms 8 of the clutch into contact with the inclined wall of the cone-shaped end of the casing 4, and thereby bringing 80 the serrated lips 9 into engagement with each other and into engagement with the pins 1 when the latter is inserted within the protector.

It will be noted that the casing 4 is open 85 at its sides and that the tube 10 is removably engaged with the clutch 6 within the casing. Due to this construction it will be readily understood that the clutch 6 is adapted to be removed from within the casing 90 after the tube 10 has been removed therefrom.

In order to insert the pin 1 within the protector a pressure is exerted between the head 11 and the top 13 of the casing 4, so 95 as to retract the spring 14 and to allow the spring arms 8 of the clutch 6 to spread away from each other. When the pin has been properly inserted, the head 11 is released and the spring 14 exerting pressure 100 upon the body 7 of the clutch causes its arms to be brought together and its serrated lips to firmly grasp the pin 1. It will be readily noted that when the pin is to be released from the protector, the head 11 is 105 again slid away from the casing 4 to allow the spring arms 8 to spread, when the said pin may be readily withdrawn.

From the above description taken in connection with the accompanying drawings, 110 the advantages as well as the simplicity of the device will, it is thought become ap-

parent, and it is to be understood that while I have illustrated and described the preferred embodiment of the improvement as it now appears to me, changes in the minor 5 details of construction within the scope of the appended claim, may be made if desired.

Having thus fully described the invention, what I claim as new, is:—

10 In a device for the purpose set forth, a casing having its lower extremity inclined toward its lower end, the said end being formed with an opening, a clutch member within the casing constructed from a single piece of material, said clutch member 15 comprising a substantially rectangular top portion having a pair of downwardly inclined oppositely arranged depending resilient side arms, said arms having their lower extremities formed to provide a pair

of serrated lips disposed opposite each other, said top portion formed with an opening, a tube removably mounted within the said opening and projecting through the casing, a hollow head for the tube, a spring member adapted to exert its pressure upon the clutch to force its arms against the inside of the casing and to compress the lips of the said arms, said casing being open at its sides so as to permit removal of the said clutch member therefrom upon removal of 30 the said tube from the casing.

In testimony whereof I affix my signature in presence of two witnesses.

ROBERT L. SLONAKER.
